UNITED STATES PATENT OFFICE.

ERNST GEORG BERNHARD KÖRTING, OF MARIENDORF, NEAR BERLIN,
GERMANY.

RETORT-HEATING APPARATUS.

No. 825,912.

Specification of Letters Patent.

Patented July 17, 1906.

Application filed April 21, 1905. Serial No. 256,708.

To all whom it may concern:

Be it known that I, ERNST GEORG BERNHARD KÖRTING, a citizen of the Empire of Germany, residing at Mariendorf, near Berlin, Germany, have invented certain new and useful Improvements in Retort-Heating Apparatus; and I do hereby declare the following to be a full, clear, and exact description of the invention, such as will enable others skilled in the art to which it appertains to make and use the same.

This invention relates to means for heating retorts of great length, and especially in coke and gas production.

15 Where the retorts to be heated exceed a length of about three meters, it has been found necessary to take some steps to insure the distribution of the heat, as otherwise the extremities of the retorts lying more closely adjacent to and remote from the furnace or heat-generating chamber would be unequally heated. It has been sought to solve this difficulty by providing in the generating-chamber or the retort-chamber partitions to separate and direct the heating-gases and also to use a plurality of generating-chambers feeding the different compartments of the retort-chamber with combustible gases. The disadvantage has been that where separate heating-chambers are provided they must be separately charged and regulated and where one is used the partitions cannot be made to equally distribute the heat, and as a result in either case the retorts are unequally heated, thereby impairing the efficiency of the operation, adding to the cost, and depreciating the quality of the product.

The object of this invention is the arrangement of coking-retorts and heat-generating chambers so as to simplify the charging and to reduce the necessity of constant supervision, while insuring the equal heating of the different portions of the retorts.

For purposes of elucidation in the accompanying drawings an embodiment of the invention is illustrated.

In the drawings, Figure 1 is a vertical transverse section on the line 1 1 of Fig. 3. Fig. 2 is a similar section on the line 2 2 of Fig. 3. Fig. 3 is a vertical longitudinal section on the line 3 3 of Fig. 1. Fig. 4 is a similar section on the line 4 4 of Fig. 1, and Fig. 5 is a similar section on the line 5 5 of Fig. 1.

Referring to the drawings in detail, the

structure in which the retorts *a* lie is divided 55 transversely by a wall *b*, thus forming the retort-heating chamber into two compartments *c'* and *c''*, both of which are supplied with combustible gases from the twin generator, which is provided with the stepped grate *t* 60 and the charging-door *e*. The generator is divided into two parts *d* and *f* by a partition *g*, which projects downwardly from the floor of the retort-heating chamber. The lower edge of the partition *g* occupies a position 65 slightly lower than the normal level of the fuel in the generating-chamber, the two compartments *d* and *f* being thereby isolated except for the communication through the porous body of fuel therein.

70 The front generator-compartment *d* communicates by channels *h'* with the front retort-compartment *c'*, which channel serves for the passage from the compartment *d* to the compartment *c'* of the combustible gases 75 generated from the fuel. As the gases pass through the channels *h'* they come into contact and are thoroughly mixed with preheated air or other combustion-supporting gases from the channels *i'*, as will be seen from Fig. 80 1. This air is warmed during its circuitous passage from the inlet *n'* through the channels *k'* and the openings *m'*, connecting said channels. The incandescent-gas mixture plays about the retorts *a* in the retort-compartment *c'* and having given up its heat to 85 said retorts passes out through the openings *o'* and through the circuitous channels *p'* and openings *q'* to the smoke-flue *s'*. It will be seen that the spent gases escaping from the 90 retort-compartment serve to preheat the incoming air, the channels *k'* and *p'* lying alongside each other in the side walls of the structure.

95 The rear generator-compartment *f* communicates with the rear retort-compartment *c''* by means of channels *h''*, and the combustible gases from said generator-compartment *f*, passing through the channels *h''*, are intermixed with incoming air through the channels 100 *i''*, the preheating of the air being effected by passing through the openings and channels *k''* 105 *m''* and serving to heat that portion of the retort lying in the rear chamber *c''*, and the spent gases being carried off through *o'', p'', q'',* and *s''* in the same way as described with relation to the gases generated in the forward generator-compartment *d*. It will thus be

seen that the one twin generator serves to supply combustible gases to both the retort-compartments c' and c^2 , the gases generated in the compartment d going to the compartment c' and those generated in the compartment f going to the compartment c^2 , whereby both extremes of the retorts a lie in independent retort-chambers and are yet heated by combustible gases generated from a single charge of fuel, thus providing for the maintenance of approximately the same temperature throughout the retorts.

In order to even more efficiently govern the heating of the retorts and bring the regulation thereof entirely within the control of the operator, dampers u' and u^2 are provided in the outlet-flues from both retort-compartments at a point adjacent to the smoke-discharges s' and s^2 . These dampers are independently adjustable to shut off to a greater or less degree the escape of the spent gases from either retort-compartment. It will be readily understood that while both dampers are left open the combustible gases will pass in substantially equal quantities from the generating-compartment d and f through the compartment c' and c^2 , maintaining substantially the same temperature in each. If, however, the damper u' be closed in a greater or less degree, the effect will be to exert back pressure through the channels k' , damming the combustible gases in the compartment c' and prevent the entrance of more gas from the generating-compartment d . The result will be that the combustible gases will pass through the porous fuel in the generator-chamber into the compartment f , and thence into the retort-compartment c^2 , heating the rear portion of the retorts to a higher temperature. If, on the other hand, the damper u' be opened and the damper u^2 be closed, the effect will be reversed. It will thus be seen that equitable heating of the entire length of the retorts is provided for, coupled with means for efficiently regulating the heating of the same.

It will be obvious that the compartments into which the generating-chamber and the heating-chamber are divided may be multiplied to correspond to an increased length of the retort to be heated. Ordinarily with a retort of three meters in length two compartments would suffice.

Having thus fully described my invention, what I claim as new, and desire to secure by Letters Patent of the United States, is—

1. The combination, with bodies to be heated, and a heating-chamber containing said bodies and divided into isolated compartments longitudinally of said bodies, of a heat-generating chamber, partitions separating the upper portion of the generator-chamber into compartments, and passages leading from each generator-compartment to each heating-compartment.

2. The combination, with elongated bodies to be heated, and a heating-chamber containing said bodies and divided into isolated compartments longitudinally of said bodies, of a heat-generating chamber, partition-walls extending downwardly to a point below the normal level of the fuel and forwardly the upper portion of the generator-chamber into compartments corresponding in number to the heating-compartments, and passages leading from each generator-compartment to each heating-compartment. 70

3. The combination, with elongated bodies to be heated, and a heating-chamber containing said bodies and divided into isolated compartments longitudinally of said bodies, of a heat-generating chamber, partition-walls extending downwardly to a point below the normal level of the fuel and separating the upper portion of the generator-chamber into compartments corresponding in number to the heating-compartments, passages leading from the upper portion of each generator-compartment to each heating-compartment, and separate discharge-passages for the spent gases from each of the heating-compartments. 85

4. The combination, with elongated retorts to be heated, and a heating-chamber containing said retorts and divided into compartments longitudinally of said retorts, of a heat-generating chamber, partitions extending downwardly and separating the upper portion of the generator-chamber into compartments, and passages leading from each generating-compartment to each retort-heating compartment. 95

5. The combination, with elongated retorts to be heated, and a heating-chamber containing said retorts and divided into isolated compartments longitudinally of said retorts, of a heat-generating chamber, partitions extending downwardly to a point below the normal level of the fuel and separating the upper portion of the generator-chamber into compartments corresponding in number to the retort-heating compartments, and passages leading from each generator-compartment to each retort-heating compartment. 105

6. The combination, with elongated retorts to be heated, and a heating-chamber containing said retorts and divided into isolated compartments longitudinally of said retorts, of a heat-generating chamber, partitions separating the upper portion of the generator-chamber into compartments corresponding in number to the heating-compartments, passages leading from each generator-compartment to each heating-compartment, independent outlet-passages from the retort-heating compartments, and dampers arranged in said outlet-passages. 115

7. The combination, with elongated retorts to be heated, and a heating-chamber containing said retorts and divided into isolated compartments longitudinally of said re- 130

torts, of a generator-chamber for combustible gas, partitions extending downwardly to a point below the normal level of the fuel and separating the upper portion of the generator-chamber into compartments, passages leading from each generating-compartment to each heating-compartment, air-passages for supplying air to the combustible gases, and independent outlet-passages from each retort-heating compartment.

8. The combination, with elongated retorts to be heated, and a heating-chamber containing said retorts and divided into compartments longitudinally of said retorts, of a generator-chamber for combustible gases, partitions extending downwardly to a point below the normal level of the fuel and separating the upper portion of the generator-chamber into compartments corresponding in number to the retort-heating compartments, passages leading from each generator-compartment to each heating-compartment, passages for supplying preheated air to the combustible gases upon their entrance to the heating-chamber, independent outlet-passages from the retort-heating compartments, and dampers arranged to control said outlet-passages.

9. The combination, with elongated bodies to be heated, and a heating-chamber containing said bodies and divided into isolated compartments longitudinally of said bodies, of a generator-chamber for combustible gases, partitions extending downwardly to the normal level of the fuel and separating the upper portion of the generator-chamber into compartments corresponding in number to the heating-compartments, passages lead-

ing from each generating-compartment to each heating-compartment, a circuitous passage for supplying air to the combustible gases upon their entrance to the heating-compartments, and outlet-passages for the spent gases from the heating-compartments, said outlet-passages lying adjacent to the air-supply passages and extending in an opposite direction.

10. The combination, with elongated retorts to be heated, and a heating-chamber containing said retorts and divided into isolated compartments longitudinally of said retorts, of a generator-chamber for combustible gases, partitions extending downwardly below the normal level of the fuel in the generator-chamber and separating the upper portion of the chamber into compartments corresponding in number to the retort-heating compartments, passages leading from each generator-compartment to each heating-compartment, circuitous passages for supplying air to the combustible gases upon their entrance to the retort-heating compartments, separate outlet-passages leading the spent gases from the retort-heating compartments, the outlet-passages and air-supply passages extending in opposite directions adjacent to each other, and independently-operable dampers arranged in the outlet-passages.

In testimony whereof I have hereunto affixed my signature in the presence of two witnesses.
